SLIDING WINDOW SASH HOLDER

Harry Schwartzmann, New York, N. Y.

Application August 2, 1949, Serial No. 108,137

6 Claims. (Cl. 292—74)

1

The present invention relates to sliding window sash holders, i. e., to devices for use in connection with any more or less conventional sliding window sash to take the place and perform the function of the customary counter-weight and pulley for holding the sash in predetermined positions of vertical adjustment.

More particularly, the present invention provides a small and inexpensive device which can be readily installed in fully concealed position on the sash, or on the frame if desired, and which will securely hold the sash in any position of vertical adjustment without requiring any unlocking, unlatching or other manipulation for release to permit movement of the sash to a new position.

A principal object of the invention is to provide a device of the character described which will operate to hold the sash by frictional engagement between the sash and frame.

A further important object is to provide the device with a simple mechanism which will release or relieve the holding friction automatically as movement of the sash to a new position is initiated, so that lowering the sash and elevating it will not require overcoming the full frictional force or value which is used in holding it.

Other objects are to provide a device of the character indicated which can be constructed of a few inexpensive parts combined in an assembly of very small size which can be readily installed so as to be entirely hidden in operative position and which will be thoroughly durable, foolproof and dependable in operation.

Other and further objects and advantages of the invention will be apparent to those skilled in the art from the accompanying drawing and the following description thereof, in which a preferred embodiment is disclosed.

In the accompanying drawing,

Figure 1 is a side elevational view of one corner of a conventional type of sliding window sash and the cooperating window frame, partly broken away to show in side elevation the preferred embodiment of the device which forms the subject of the present application;

Fig. 2 is a vertical sectional view on a larger scale taken on the line 2—2 of Fig. 3;

Fig. 3 is a horizontal sectional view taken on the line 3—3 of Fig. 2; and

Fig. 4 is an exploded perspective view of the device.

As has been explained, the device provided by the invention is adapted to be used as a substitute for the familiar counterweight which is cus-

2

tomarily carried at the end of a sash cord which is trained over a pulley journaled in the top of the window frame and which balances the sash so as to support it in predetermined positions of vertical adjustment. The invention substitutes frictional force for counterbalancing, which substitution has been heretofore provided in the art, but the invention is distinguished from all prior art devices with which I am acquainted by reason of the fact that it is operative automatically on the initiation of vertical movement of the sash to release or relieve the holding friction so that the unbalanced sash can be lowered or raised with a minimum of applied force. To this end the device includes a novel type of coupling by which a friction shoe is mounted in a base element in such a way that the shoe is normally pressed outwardly from the base element to provide a high degree of holding friction but is retracted toward the base element to decrease the frictional force automatically at the beginning of the movement of the sash in an up or down direction.

Referring now to the drawing, the reference numeral 1 designates a window sash mounted for vertical sliding movement in a frame 2. The sash includes side rails 3, and the frame includes a parting strip 4 which cooperates with a frame base 5 and a closing strip which is not shown but which is mounted parallel to the parting strip to provide a channel runway in which the side rail 3 of the sash is vertically slidable.

Either the sash member or the frame member is pocketed to provide a recessed mounting space for the device which forms the subject of the present invention. I prefer to mount the device in a recess formed in the sash member, so that it will move with the sash member and will bear frictionally against the bottom 5 of the frame member channel, but it will be understood that this specific mounting is simply the preferred form and that in some cases the arrangement can be reversed and the device mounted in the frame member for bearing against the side rail of the sash member.

In the case of some weatherstripped windows it may be found desirable to form the device-receiving pocket in the base 5 of the frame member, or in the strip 4 or cooperating closing strip 50 of the frame member, or in the front or rear surface of the side rail of the sash member, instead of in the side edge thereof as shown in the drawing, in order to avoid interference with the weatherstripping rib and groove. It is to be understood that the precise mounting position of

the device forms no essential part of the invention.

The device comprises a base element 6, best made of stamped sheet metal of relatively heavy gauge, having a bottom 7 and integral upturned flanges or side walls 8, so that the base is substantially channel-shaped. The base is affixed permanently in the recess, here shown at 9 in the side edge of the side rail 3 of the sash member, in any convenient manner, as by drilling a pair of holes in the bottom 7 for the reception of wood screws 10.

Spring means, which by way of example may be a leaf spring 11, is mounted in the base as by riveting, soldering or spot welding the central portion of the spring to the middle of the bottom of the base so that two legs of the spring will extend obliquely out toward the lips of the base channel and yieldably urge outwardly the friction shoe which is coupled to the base and will now be described.

This friction shoe, designated 12, comprises a generally channel shaped element which can be made as a heavy gauge sheet metal stamping so that it includes a friction face 13 having rearwardly directed from its side edges a pair of flanges or walls 14, each of which is perforated at 15 to mount a pin 16 in permanently fixed position with its ends protruding slightly from the planes of the side walls 14. The shoe is applied by nesting it in the base, over the ends of the spring 11, with the side walls 14 lying close to and parallel with the side walls 8 of the base, between these latter side walls and the side edges of the spring 11. The pin 16 is then driven through enlarged openings 17 provided in the base side walls 8, and through the holes 15 in the side walls of the shoe, so that the base and shoe are permanently coupled together with the spring 11 compressed between them, with the shoe yieldably projected from the base to a limit fixed by the shape of the opening 17.

The shape of the opening 17 is important. As shown in the drawing, each opening is comparatively large and is approximately semi-circular in outline, with the diameter or straight side of the semi-circle lying in the plane of the bottom 7 of the base and with the arcuate edge of the opening curving out fairly close to the free or outer edge of the side wall 8.

This relationship is such that the coupling of the base and shoe is loose, so that the shoe is free to move inwardly into the base channel, against the expansive force of the spring 11, and is free to slide lengthwise of the base to a limited extent as the pin 16 follows the curvature of the openings 17 upon inward movement of the shoe. The movement of the shoe can thus be made a compound one, having inward and lengthwise components.

With the device mounted between the sash and frame members, being affixed permanently to one of these members, the shoe is biased outwardly from the base so that its face 13 makes good frictional engagement with one of the members 1 or 2. The value or degree of this frictional engagement is made sufficient, by the relative proportions of the parts, to hold the sash in any vertically adjusted position to which it may be moved in the frame. Thus the sash is securely held against any tendency to fall by virtue of its weight or by any accidental forces that may be imposed on it.

This frictional holding force must of course be overcome when the sash is to be moved to a

new vertically adjusted position. An important feature of the invention consists in so forming the coupling connection of the base and shoe that the shoe will be automatically displaced, preferably by a camming action, into a retracted position in the base whenever sliding movement of the sash to a new position is begun. This camming action will now be explained.

In any adjusted position of the sash relative to the frame, the ends of the pin 16 will automatically seat themselves at the high point of each of the openings 17, i. e., at the point of greatest distance from the plane of the bottom 7 of the base. When the sash is pulled or pushed up or down, the shoe 12 tends to remain immovable in the frame runway, but after sliding movement of the sash has progressed beyond a very small distance, the backwardly curving edge of the opening 17 acts against the pin and tends to move it inwardly toward the bottom 7 of the base. This of course has the effect of retracting the whole shoe into the base and withdrawing the friction face 13 from that surface of the frame runway against which it is pressed by the spring 11. The extent of this movement is sufficient to release or relieve the pressure of the shoe on the runway surface, so that the sash will slide easily in an up or down direction as may be desired. Thus it is not necessary in making such movements of the sash to overcome the full frictional force by which the shoe normally holds the sash in any adjusted position. When the sash is brought to rest the shoe rocks relatively to the base and the pin seats itself again in the high points of the openings 17, thus exerting strong holding friction on the channel and fixing the sash at its new position.

It will be appreciated that the device is small, inexpensive, thoroughly durable, and can easily be mounted in completely hidden position in either the frame member or, as is preferred, in the sash member, and that it provides a superior substitute for a counterweight installation without requiring any great amount of force or any unlatching or other manipulation when the window sash is to be moved to some new position. Thus the objects and purposes of the invention are accomplished.

I claim:

1. A device for holding a vertically sliding window sash member in predetermined adjusted positions relatively to a fixed window frame member comprising a shoe for engaging frictionally with one of the members when the sash member slides in the frame member, projections laterally extending from the shoe, an elongated channel-shaped base adapted to be mounted lengthwise in the other member with its bottom affixed thereto and having an opening in each of its side walls receiving one of said projections, each opening being defined by a marginal cam edge having at its mid point a portion spaced farthest from said bottom and having portions diverging therefrom upwardly and downwardly toward the ends of the channel and inwardly toward the bottom thereof so that the shoe is held captive on the base with freedom for limited movement toward and away from said bottom and lengthwise thereof, and a spring mounted in compression directly between the bottom and the shoe for urging the shoe yieldably outwardly from the bottom, whereby said cam edge cooperates with said projections for forcing the shoe inwardly against the tension of said spring and toward the base bottom when the shoe is moved lengthwise relatively

to the base in response to movement of the sash member either upwardly or downwardly in the frame member.

2. A device as claimed in claim 1 in which said projections are the ends of a pin extending laterally through the shoe and into the openings in the side walls of the base.

3. A device as claimed in claim 1 in which the spring is a leaf spring reacting directly between the shoe and base elements of the device with a flat central portion engaging one of said elements and a pair of upturned end portions engaging the other.

4. A device as claimed in claim 1 in which said projections are the ends of a pin extending laterally through the shoe and into the openings in the side walls of the base and in which the spring is a leaf spring reacting directly between the shoe and base elements of the device with a flat central portion engaging one of said elements and a pair of upturned end portions engaging the other.

5. A device as claimed in claim 1 in which each of the openings is large relatively to the cross sectional area of the projection which is received in

it and is of substantially semicircular shape with the mid-point on its arc farthest from the base bottom.

6. A device as claimed in claim 1 in which each of the openings is relatively large and of substantially semi-circular shape with the mid-point on its arc farthest from the base bottom and in which said projections are the ends of a pin of much smaller diameter than said openings which extends laterally through the shoe and into the openings.
